CLAIM

We claim the ornamental design for a washing machine, as shown and described.

DESCRIPTION

FIG. 1 is a front perspective view of a washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof; and,

FIG. 8 is an enlarged view of the encircled portion shown in FIG. 4.

The short dash-dash broken line in the figures shows unclaimed portions of the washing machine and the dot-dot-dash broken line encircling portions of the claimed design in FIGS. 4 and 8 is for illustrating enlargements; the broken lines form no part of the claimed design.
